[57] CLAIM

The ornamental design for a cell phone receptor, as shown and described.

DESCRIPTION

FIG. 1 is a front elevational view of a cell phone receptor showing my new design;

FIG. 2 is a left side elevational view thereof;

FIG. 3 is a right side elevational view thereof;

FIG. 4 is a rear elevational view thereof;

FIG. 5 is a top plan view thereof;

FIG. 6 is a bottom plan view thereof;

FIG. 7 is a front perspective view thereof;

FIG. 8 is a rear perspective view thereof; and,

FIG. 9 is a front elevational view of a second embodiment of my new design, the other surfaces thereof being same in appearance as the first embodiment.

The broken line showings of the electrical cord are for illustrative purposes only and form no part of the claimed design, the portion of the article hidden behind the broken line disclosure is not a part of the claimed design.
